UNITED STATES PATENT OFFICE

2,427,036

SHEET PULP CONTAINER DRYER, ETC.

Lee M. Wiley, Marion, Ind., assignor of one-third
to Julian T. Lett, and one-third to Reely B.
Wiley, both of Marion, Ind.

Original application May 27, 1942, Serial No.
444,671. Divided and this application Decem-
ber 1, 1943, Serial No. 512,412

4 Claims. (Cl. 34—207)

1

This invention relates to the substantial de-
hydration and final formation of deep seamless
containers formed from flat fibrous sheet stock
suitably dampened and/or impregnated, coated
or the like.

The chief object of this invention is to reduce
the number of finishing operations and operating
time over that initially and broadly disclosed in
co-pending application Serial No. 288,343, filed
August 4, 1939, entitled, "Sheet pulp container
forming process and apparatus therefor," now
Patent No. 2,337,581 dated December 28, 1943, and
specifically made a part hereof for so much as
may be necessary for an understanding of the
present invention.

As disclosed in said patent, paper sheet stock
is subjected to moisture and other liquid ma-
terials, then blanked to the required size and
shape, then fluted in blank ejection to a receiver
mold and then initially molded. A modified
form of blanking, creasing and preforming in a
receiver mold is also disclosed in the copending
application Serial No. 334,823 filed May 13, 1940,
and entitled "Process and apparatus for form-
ing seamless fibre stock containers," now Patent
No. 2,296,889 dated September 29, 1942, and same
is also made a part hereof. This partially formed
article, formed as aforesaid, from which excess
moisture, liquid, et cetera, has been mechanically
expressed by pressure, is automatically discharged
from the receiver mold to an article support on
an endless conveyor having intermittent move-
ment since the receiver mold is turret mounted
and indexable from station to station.

For the purposes of this invention this dis-
closure starts with said endless conveyor. Here-
in the same passes through a two-stage dryer
and then to a stuffer device.

One chief feature of the present invention re-
sides in the two-stage heater and article travel
therein.

Other objects and features of the invention will
be set forth more fully hereinafter.

The full nature of the invention will be under-
stood from the accompanying drawings and the
following description and claims:

In the drawings:

Fig. 1 is a somewhat diagrammatic elevational
side view of the heater, the subject matter of
this invention and the immediate juxtapositioned
portion of the article transfer device associated
therewith.

Fig. 2 is a similar top plan view of same.

Fig. 3 is an elevational view of a portion of
the conveyor structure included in the heater.

2

Figs. 4 and 5 are central section and end ele-
vational views, respectively, of the parts shown
in Fig. 3.

As initially stated herein, the blank stock prior
5 to blanking has been subjected to conditioning
that is the application of moisture, et cetera.
The resulting blank is then creased or fluted in
a predetermined manner prior to reception by a
10 receiver mold in which a large percentage of
the moisture (free moisture) is pressure ex-
truded, et cetera. The conveyor mentioned, to
which the receiver molds discharge partially
formed articles is indicated by the numeral 10
in Fig. 1.

15 As distinguished from the prior copending dis-
closures, the upper run of the conveyor enters
the oven 11 through opening 12. This run then
passes to sprocket 13 and then back and forth
over successive sprockets 14 and 15 gradually ris-
ing in the oven.

20 The oven includes a baffle plate 16 that termi-
nates at 17 so that run 18 lies above said baffle.
Sprocket 19 above the plate 16 directs the con-
veyor to sprocket 20 above another and offset
25 baffle 21. Baffle 16 forms a lower and dehydrating
chamber 22 which in in the present instance, con-
tains six runs of the conveyor 10.

20 Baffles 21 and 16 form a superposed preheat-
ing chamber 23 in which there are approximately
30 three runs of the conveyor 10.

Chamber 23 is termed the preheating chamber
because the heat in the first chamber is pri-
marily for drying and warming the articles,
whereas the heat in chamber 23 softens or melts
35 the size, resin, etc., to insure flow thereof so that
upon subsequent pressure solidification, etc., a
substantially finished article results. Thus, heat-
ing in chamber 23 after drying in dehydrating
chamber 22 is a prerequisite to final formation,
40 wherefore the heating step is termed preheat-
ing and chamber 23 the preheating chamber.

These chambers 22 and 23 communicate by
throat 24 formed by baffles 16 and 21. The pre-
heating chamber is elongated and overhangs at
45 25 the dehydrating chamber at the discharge
end of the oven, such discharge passage being
indicated at 25 in which is mounted sprockets
26. The wall of the dehydrating chamber is
extended upwardly at 10a forming a baffle in
50 turn providing a throat 27 between the preheat-
ing chamber 23 and discharge passage 25.

Near the base of the oven 11 but outside of
same and approximately below sprockets 26 are
55 sprockets 28 adjacent opening 29 which is ap-
proximately opposite opening 12. The lower and

return run of the conveyor 10 is indicated by 30 and herein passes from the oven 11 through opening 12 to the transfer station at the turret type former having the receiver molds before mentioned and not shown herein but shown in said applications aforesaid. Following article transfer to the conveyor 10 it and said articles enter the oven 11 at opening 12 as aforesaid.

Preferably conveyor travel is intermittent to permit conveyor and receiver mold registration for article transfer during the turret dwell period during which one set of receiver molds receives and performs the blank, another set pressure forms same, and another set discharges articles to conveyor 10 herein all as set forth in the first mentioned copending application.

It is to be understood the conveyor 10 diagrammatically illustrated in Fig. 1 includes two spaced chains of sprocket link type suitably connected together at predetermined distances apart by transverse members 31—see Fig. 2—central part.

Referring now to Figs. 3 to 5, it will be noted tube 31 is tubular and spaced along the same are mushroom-like article supports having the head 32 and stem 33 rigid therewith. As shown in Figs. 4 and 5, tube 31 is non-circular and a support base 34 is adjustably but rigidly mounted on the tube by cap 35. A shank 36 is socketed at 37 to receive the lower end 33b of stem 33 shouldered at 33a. The socket is split at 37a and clamp bolt 37b rigidly secures the stem 33 in said socket.

It will be appreciated that support 32—33 can be readily removed and replaced by another support whenever another type of article is fabricated. This is effected by loosening 37b. Also, it will be understood that by removing cap 35, the entire individual support can readily be removed without disturbing other supports or the conveyor. By loosening the caps 35 the supports on tube 31 can be readily adjusted thereon as desired or required with regard to spacing between supports in transverse alignment.

The immediate connection of the ends of tubular member 31 to the chains of the conveyor 10 is shown in Figs. 3 and 5. Herein the tubular element 38 has a center which is the center of a roller chain link. Mounted thereon is ball race 39 and mounted thereon is socket 40 having depending portion 41 which at its lower end is notched, or bifurcated as at 42 to nest or seat the adjacent end of tube 31. A bolt 43 extends through registering apertures 31a in the seated end of the tube and is threaded into portion 41 at 43, portion 41 being relieved or recessed at 41a for bolt end reception.

From the foregoing it is noted that all mushroom supports, of which there are seven, with the cross member 31 and end members 41 are one rigid unit which swivels about the center of spaced members 38 of the sprocket chain conveyor 10 and upon races 39.

The comparative weights are such that the parts always assume a position, when not positively constrained, such that heads 32 are always uppermost. This means the articles nested therein always are retained on the supports in conveyor travel from the receiver mold transfer station to and through the oven and at the discharge end thereof. Certain of the sprockets are power driven and certain are of idler type. Operation of the conveyor, as stated, is preferably of intermittent character.

Reference will now be had more particularly to Figs. 1 and 2 for a disclosure of the oven

construction, control and operation. To facilitate access to the interior of the oven, which is required for sprocket, chain, et cetera inspection, repair and lubrication, doors or panels of sufficient size of detachable or hinge type, are provided whenever necessary or convenient. Same, however, for clearness are not herein illustrated. The oven likewise is of insulated character but such heat insulation is similarly not illustrated for like reasons. Preferably the oven is of skeleton frame type with insulation walls, et cetera, suitably secured thereto. Details of construction naturally are optional in character.

In Fig. 1 there is illustrated a plurality of heat supply ports 44 in the dehydrating chamber 22. Herein two are illustrated. The numeral 45 indicates a plurality of exhaust ports and of like number. In the preheating chamber 23 a plurality of heat supply ports 46 are provided. Herein two are shown.

For convenience the oven heat is supplied by air heated externally of the oven. Damper controls et cetera, are intentionally omitted for clearness. Suffice to state, the external source of heat may be of electrical character as indicated at 47, although in certain applications the source of heat may be of other character such as by steam coils or gas or oil burning equipment.

The air heated in unit 48 is drawn from same by fan 49 and supplied to conduits 50 which connect to the supply ports 44 and 46. The fan draws this air through unit 48 from conduits 51 connecting at one end to unit 48 and at the opposite end to the discharge ports 45. Thus recirculation is effected reducing heat cost to a minimum.

For a better understanding of the foregoing portion of the invention, the following is set forth by way of example only and same is illustrative and not restrictive in character.

The conveyor 10 is endless and there will be about twice as many supports in the dehydrating chamber as there are supports in the preheating chamber at any one time and in the example illustrated. The temperature in the dehydrating chamber normally exceeds that in the preheating chamber. Controls, not illustrated, maintain chamber temperatures within predetermined desired temperature ranges.

Observe from Fig. 1 that the three associated stuffing mechanism pairs of sprockets 54, 55 and 56 are so positioned relative rollers 26 and 28 that sprocket chain stretching in the oven is not required. This is because while sprockets 26 and 28 are in substantial vertical alignment, such alignment is not tangential to the sprockets 54 and 56 which are also vertically aligned. The offsetting between these alignments, see Fig. 1, therefore, permits sprockets 54, 55 and 56 to reciprocate as a unit upon support 57 and without chain stretching, as it were. Such reciprocation is to present one transverse series of mushroom supports to one transverse series of receiver molds 62 upon an indexable turret 61.

This application is a division of application Serial No. 444,671 filed May 27, 1942, Patent 2,377,392, entitled "Sheet pulp container forming process and apparatus therefor" and same accordingly is made a part hereof.

While the invention has been illustrated and described in great detail in the drawings and foregoing description, the same is to be considered as illustrative and not restrictive in character.

The several modifications described herein as

5 well as others which will readily suggest themselves to persons skilled in this art, all are considered to be within the broad scope of the invention, reference being had to the appended claims.

The invention claimed is:

1. In a forced circulation type oven structure having an endless article conveyor and a heating system, the combination of a pair of oven type chambers, means providing communication therebetween at the adjacent ends of the chambers, the conveyor successively passing through the chambers and intermediate communication means, means in each chamber insuring sinuous travel of the conveyor therethrough, heat supplying input means at the remote ends of the chambers, exhaust means at the adjacent ends of the chambers, and conduit means external to the chambers and connecting said intake and exhaust means to the heating system for recirculation purposes, the intake and exhaust means to and from the chambers being of multiple type. 20

2. An oven structure as defined by claim 1 wherein a singular housing includes both chambers, and the communication providing means comprises baffle means extending towards each other from opposite ends of the housing and forming a throat spaced from the top, bottom and ends of the housing, the exhaust means being disposed contiguous to the throat. 25

3. A multiple chamber oven construction comprising in combination a singular housing, baffle means therein forming a plurality of communicating chambers, each chamber having inlet and outlet portions, an article supporting endless conveyor advanceable therethrough, means for causing said conveyor to move sinuously in each chamber, means for supplying heat to the chambers at the inlet portions thereof, said heat supplying means having a common source, and means for removing heat from the chambers, 40

one chamber being larger than the other and each having therein approximate portions of the conveyor proportional to the chamber volumes, the heat removing means being disposed adjacent the outlet portion of the larger chamber whereby the smaller chamber has a greater temperature therein than the larger chamber, and the chambers where they communicate one with the other have an approximate common temperature, temperature change in one chamber increasing with conveyor advance and in the other chamber decreasing with conveyor advance. 10

4. An oven structure as defined by claim 3 wherein said baffle means comprises baffles extending from opposite ends of the housing and forming a throat spaced from the top, bottom and ends of the housing, the inner ends of the baffles lapping each other although spaced apart for article and conveyor clearance purposes. 15
